REPRODUCING ARM

Filed March 16, 1933

UNITED STATES PATENT OFFICE

1,963,673

REPRODUCING ARM

Carlos E. Patino, Long Island City, N. Y.

Application March 16, 1933, Serial No. 661,063

14 Claims. (Cl. 274—1)

This invention relates to reproducing arms for use in connection with disk records, and especially arms of the amplified reproduction type electrically placed in communication with the amplifier; and the object of the invention is to provide means for mounting and manipulating the arm with respect to a disk record so as to maintain the needle of the reproducer in a vertical plane at right angles to the center or what may be termed the pitch line of the sound producing grooves of the record to eliminate wear on the side edges of said grooves as well as prevent accidental displacement of the needle from the groove and the scratching or marring of the record caused thereby; a further object being to provide means for rotatably or pivotally supporting the sound reproducing head of the arm in connection with the free end of said arm; a further object being to provide means at the pivot or fulcrum end of the arm for imparting rotary movement to the sound reproducing head independent of the rotary movement of said arm; a further object being to provide means for swinging the pivoted end of the arm to raise and lower the same with respect to the record to facilitate the attachment and detachment of records with respect to the usual table supporting said record; a further object being to provide means for adjusting the arm including its pivot to properly position the needle of the reproducer with respect to the record; a still further object being to provide means including a plug at the pivoted end of the arm for placing the reproducer in electrical communication with an amplifying unit; and with these and other objects in view, the invention consists in a device of the class and for the purpose specified, which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic plan and sectional view showing one of my improved arms and indicating the method of its use.

Fig. 2 is a section on the line 2—2 of Fig. 1;

Fig. 3 is a section on the line 3—3 of Fig. 2; and,

Fig. 4 is a side elevation of the device with part of the construction broken away.

In Fig. 1 of the drawing, I have shown for the purpose of illustrating my invention a part of a

disk record 10, which rotates about the axis 11 in a suitable reproducing machine which forms no part of my invention. At 12, I have shown a reproducer arm rotatable on the pin 13 which is supported in a suitable casing 14, the latter being secured to a part of the machine through a bracket 15 in connection with which the casing 14 including the arm 12 has a pivotal mounting as indicated at 16, note Fig. 2 of the drawing, to permit the arm to swing upwardly and downwardly with respect to the record 10.

In attaching my improved arm to a machine and especially when sold independent of the reproducer machine, I preferably provide the casing 14 with a longitudinal, beveled wall tongue 14a which slidably engages a channeled block 17 and is held in different positions of adjustment by a set screw 18, note Figs. 2 and 4. The arm 12 is tubular in form as clearly seen in Figs. 1 and 2 of the drawing, the outer end 12a being slightly enlarged to receive a block 19 of insulating material to which is coupled a tubular extension on an electric reproducer 21, which carries the reproducing needle 22. It will be noted on a consideration of Fig. 1 that the enlargement 12a has a slot 23 through which the tube 20 is free to pass as the reproducer head 21 rotates on the axis 24, provided in the end of the arm. At the inner end of the tubular support 20 are two electric spring contacts 25, 25a which complete circuits with contacts 26, 26a, secured to the block 19 and to which the circuit wires 27, 27a are attached, it being understood that the contacts 25, 25a are in circuit with the reproducer head 21 and the reproducing mechanism thereof so as to transmit the sound vibrations from the grooves 10a of the record 10 to a suitable amplifying unit as in other apparatus of this class.

In the construction shown, the wires 27, 27a pass through an opening 28 formed in the bottom of the pivoted end of the arm 12 adjacent the pivot 13 and also through an elongated opening 29 formed in the top of the casing 14 and extend into the casing, the wire 27 being coupled with an electric resistor 30 arranged in the casing 14 and from the resistor, a wire 30a is grounded to the ground side 31 of a plug socket which has a contact 32 insulated therefrom, and to which the wire 27a is connected, and a conventional plug 33 may be placed in the socket in order to couple the electric circuit with an amplifying unit arranged in spaced relation to the casing 14.

In order to counterbalance the reproducer head 21 on the end of the arm and to avoid a strain on the pivot of the arm, I provide a counterbalance

weight 34 at the inner pivoted end of the arm. This weight also serves to support the needle 22 in proper relation with respect to the grooves of the record to prevent excessive wear thereon. At 5 the lower end of the body 19 is an annular disk or pulley 19a around which a belt 35, preferably in the form of a metallic ribbon, is passed and to which the belt is secured at a predetermined point to prevent slipping of the belt on the pulley. 10 This belt passes around another pulley 36 secured to the pin or shaft 13, the belt being secured to the pulley 36 by a pin or a screw as indicated at 37 to prevent slippage.

The arm 12 has a tubular extension 38 which 15 extends into the casing 14, and secured to this extension is a cam 39 of the form shown in Fig. 3 of the drawing, and this cam cooperates with rollers 40 mounted centrally of control arms 41 and 42, one end of which is pivoted as seen at 43 20 and the other free ends of which carry rollers 44 which engage a radial pin 45 secured to the shaft 13. The outer end of the pin 45 has an upstanding part 45a which is disposed between the rollers 44 of the arms 41 and 42. A spring 25 46 couples the pivoted ends of the arms 41 and 42 and serves to support the rollers 44 in constant engagement with the pin 45.

From the foregoing description, the operation 30 of my improved arm will be readily understood when taken in connection with the accompanying drawing and the following statement. When the arm 12 including the reproducer head 21 is in the outermost position on the record 10, the parts will assume the position shown in full lines in 35 Fig. 1 of the drawing, the head 21 being disposed angularly with respect to the longitudinal plane of the arm or to a line connecting the pivots 13 and 24. In this position of the parts, it will appear that the needle 22 assumes in the outermost 40 groove or grooves of the record, a vertical position at right angles to the groove, so that the point of the needle will rest on the bottom only of the groove and will not assume an angular position or tangent with respect to the groove which 45 would cause a wearing out of the side walls of the groove as with the conventional type of mounting and method of operation of reproducer arms in connection with disk records.

From the full line position shown in Fig. 1, as 50 the record is being played and the reproducer 21 travels inwardly toward the axis 11, the head 21 is gradually swung on its pivot 24 through the action of the cam 39 which rotates or swings 55 with the arm 12. The movement of the head 21 is controlled by the operation of the arms 41 and 42 on the pin 45 when said arms are released by the cam 39, that is to say, as the cam 39 would depress the roller 40 of the arm 42 and release the roller 40 of the arm 41, the roller 44 of the 60 latter arm would move toward the roller 44 of the arm 42 and move the pin 45 correspondingly, which operation rotates the head 21 or swings the same on its pivot. In this connection, it will appear that the pin 45 is in parallel relation to 65 the needle 22, comparing Figs. 1 and 3 of the drawing, and this parallel relationship is always maintained. It will thus be seen that when the arm 12 reaches the dotted line position of Fig. 1, the pin 45 and needle 22 will be in the same alignment 70 with each other as well as in alignment with the pivots 13, 24. In this connection, it will also be understood that the needle 22 does not travel through a straight radial line with respect to the record but through an arc-shaped path, but regardless of the arc, the needle is always

80 maintained at right angles to the groove, that is to say, through a radial line extending from the axis of the record and through the point in the groove where the pointed end of the needle 22 is positioned.

85 It will also be understood that by reason of the structural arrangement employed for controlling the angular position of the head 21 or the reproducing needle 22 with respect to the arm, my improved device may be used in conjunction with records of various diameters, the head 21 assuming its proper angular relationship at all times, regardless of the diameter of the record, at least within the conventional records now employed. However, the same principles of control may be applied in the reproduction of any size of record, the dimensions of the several parts including the contour of the cam being modified to suit such changes. At x in Fig. 1 of the drawing, I have shown by dot and dash lines 90 the plane of the needle, and at x² the central line of the arm 12. This represents the innermost position of the arm with respect to the innermost grooves of the record 10.

95 It will be understood that while I have shown 100 various details of construction for carrying my invention into effect, I am not necessarily limited to the specific structural features herein shown and described, and various changes therein and modifications thereof may be made within the 105 scope of the appended claims without departing from the spirit of my invention or sacrificing its advantages.

110 Having fully described my invention, what I claim as new and desire to secure by Letters Patent, is:

115 1. A reproducer device for disk records comprising an arm pivoted at a point outwardly of the periphery of the disk in such manner as to permit the swinging movement of the free end 120 of the arm over said disk, a reproducer head carried by the free end of the arm and including the usual reproducing needle, means controlled by the swinging movement of said arm and extending through said arm for imparting independent 125 swinging movement to the head with respect to the free end of said arm, a casing at the pivoted end of said arm and in connection with which said arm is rotatably supported, and means within said casing controlling the operation of said 130 first named means.

135 2. A reproducer device for disk records comprising an arm pivoted at a point outwardly of the periphery of the disk in such manner as to permit the swinging movement of the free end 140 of the arm over said disk, a reproducer head carried by the free end of the arm and including the usual reproducing needle, means controlled by the swinging movement of said arm and extending through said arm for imparting independent 145 swinging movement to the head with respect to the free end of said arm, a casing at the pivoted end of said arm and in connection with which said arm is rotatably supported, means within said casing controlling the operation of said first 150 named means, and means for pivotally supporting the casing to a stationary support to permit swinging movement of the arm vertically toward and from said record.

155 3. A reproducer device for disk records comprising an arm pivoted at a point outwardly of the periphery of the disk in such manner as to permit the swinging movement of the free end 160 of the arm over said disk, a reproducer head carried by the free end of the arm and including 165

- the usual reproducing needle, means controlled by the swinging movement of said arm and extending through said arm for imparting independent swinging movement to the head with respect to the free end of said arm, a casing at the pivoted end of said arm and in connection with which said arm is rotatably supported and means for pivotally supporting the casing to a stationary support to permit the swinging movement of said arm vertically toward and from said record, said last named means including means for adjusting the casing with respect to said last named pivotal support. 5
4. A reproducer device for disk records comprising an arm pivoted at a point outwardly of the periphery of the disk in such manner as to permit the swinging movement of the free end of the arm over said disk, a reproducer head carried by the free end of the arm and including the usual reproducing needle, and means controlled by the swinging movement of said arm for imparting independent swinging movement to the head with respect to the free end of said arm, said means including a cam rotatable with said arm. 10
5. A reproducer device for disk records comprising an arm pivoted at a point outwardly of the periphery of the disk in such manner as to permit the swinging movement of the free end of the arm over said disk, a reproducer head carried by the free end of the arm and including the usual reproducing needle, and means controlled by the swinging movement of said arm for imparting independent swinging movement to the head with respect to the free end of said arm, said means including a cam rotatable with said arm, and a finger on the pivot of said arm controlled and operated by members engaging said cam to regulate the swinging movement imparted to said reproducer head. 15
6. A reproducer device of the class described comprising a casing, an arm mounted upon and pivoted to said casing, said arm being tubular in form and the free end thereof having a pivot in connection with which a reproducer head is mounted to swing on said pivot with respect to the free end of the arm, means mounted in said arm for coupling both of said pivots together whereby rotary movement of the first pivot will be transmitted to the second pivot to swing said reproducer head, and means in said casing actuated by said arm in the swinging movement thereof for controlling and regulating the movement imparted to said reproducer head. 20
7. A reproducer device of the class described comprising a casing, an arm mounted upon and pivoted to said casing, said arm being tubular in form and the free end thereof having a pivot in connection with which a reproducer head is mounted to swing on said pivot with respect to the free end of the arm, means mounted in said arm for coupling both of said pivots together whereby rotary movement of the first pivot will be transmitted to the second pivot to swing said reproducer head, and means in said casing actuated by said arm in the swinging movement thereof for controlling and regulating the movement imparted to said reproducer head. 25
8. A reproducer device of the class described comprising a casing, an arm mounted upon and pivoted to said casing, said arm being tubular in form and the free end thereof having a pivot in connection with which a reproducer head is mounted to swing on said pivot with respect to the free end of the arm, means mounted in said arm for coupling both of said pivots together whereby rotary movement of the first pivot will be transmitted to the second pivot to swing said reproducer head, and means in said casing actuated by said arm in the swinging movement thereof for controlling and regulating the movement imparted to said reproducer head. 30
9. A reproducer device of the class described comprising a casing, an arm mounted upon and pivoted to said casing, said arm being tubular in form and the free end thereof having a pivot in connection with which a reproducer head is mounted to swing on said pivot with respect to the free end of the arm, means mounted in said arm for coupling both of said pivots together whereby rotary movement of the first pivot will be transmitted to the second pivot to swing said reproducer head, and means in said casing actuated by said arm in the swinging movement thereof for controlling and regulating the movement imparted to said reproducer head, said last named means comprising a cam movable with said arm and members actuated by the cam and in operative engagement with said first named pivot controlling the rotation thereof, and means for pivotally mounting the casing in connection with a support to permit vertical, swinging movement of said arm. 35
10. A reproducer device of the class described comprising a casing, an arm mounted upon and pivoted to said casing, said arm being tubular in form and the free end thereof having a pivot in connection with which a reproducer head is mounted to swing on said pivot with respect to the free end of the arm, means mounted in said arm for coupling both of said pivots together whereby rotary movement of the first pivot will be transmitted to the second pivot to swing said reproducer head, and means in said casing actuated by said arm in the swinging movement thereof for controlling and regulating the movement imparted to said reproducer head, said last named means comprising a cam movable with said arm and members actuated by the cam and in operative engagement with said first named pivot controlling the rotation thereof, and means for pivotally mounting the casing in connection with a support to permit vertical, swinging movement of said arm, and means at the pivoted end of the arm for counterbalancing the free end thereof. 40
11. A reproducer device of the class described comprising a casing, a pivot shaft mounted in the casing and extending through the upper end thereof, a reproducer arm rotatably mounted on the protruding end of said shaft and including a sleeve portion extending into said casing, a cam on said sleeve portion within the casing, two curved control arms pivoted in the casing and normally held in engagement with said cam, a finger projecting radially from said shaft within the casing and in connection with which the free end of said curved control arms operate to control rotary movement imparted to said shaft, said reproducer arm carrying at its free end a reproducer head rotatably mounted in the free end of said arm, and means coupled with said pivot shaft for placing said head in operative engagement therewith to impart rotary movement to the head in the rotation of said pivot shaft. 45

12. A reproducer device of the class described comprising a casing, a pivot shaft mounted in the casing and extending through the upper end thereof, a reproducer arm rotatably mounted on the protruding end of said shaft and including a sleeve portion extending into said casing, a cam on said sleeve portion within the casing, two curved control arms pivoted in the casing and normally held in engagement with said cam, a finger projecting radially from said shaft within the casing and in connection with which the free end of said curved control arms operate to control rotary movement imparted to said shaft, said reproducer arm carrying at its free end a reproducer head rotatably mounted in the free end of said arm, and means coupled with said pivot shaft for placing said head in operative engagement therewith to impart rotary movement to the head in the rotation of said pivot shaft, said 15 curved control arms including anti-friction rollers engaging said cam and said finger. 13. A reproducer device of the class described comprising a casing, a pivot shaft mounted in the casing and extending through the upper end thereof, a reproducer arm rotatably mounted on the protruding end of said shaft and including a sleeve portion extending into said casing, a cam on said sleeve portion within the casing, two curved control arms pivoted in the casing and normally held in engagement with said cam, a finger projecting radially from said shaft within the casing and in connection with which the free end of said curved control arms operate to control rotary movement imparted to said shaft, said reproducer arm carrying at its free end a reproducer head rotatably mounted in the free end of said arm, and means coupled with said pivot shaft for placing said head in operative engagement therewith to impart rotary movement to the head in the rotation of said pivot shaft, said 20 curved control arms including anti-friction rollers engaging said cam and said finger. 14. A reproducer device of the class described comprising a casing, a pivot shaft mounted in the casing and extending through the upper end thereof, a reproducer arm rotatably mounted on the protruding end of said shaft and including a sleeve portion extending into said casing, a cam on said sleeve portion within the casing, two curved control arms pivoted in the casing and normally held in engagement with said cam, a finger projecting radially from said shaft within the casing and in connection with which the free end of said curved control arms operate to control rotary movement imparted to said shaft, said reproducer arm carrying at its free end a reproducer head rotatably mounted in the free end of said arm, and means coupled with said pivot shaft for placing said head in operative engagement therewith to impart rotary movement to the head in the rotation of said pivot shaft, said 25 curved control arms including anti-friction rollers engaging said cam and said finger, means for pivotally and adjustably mounting said casing in connection with a support, adjacent surfaces of said reproducer arm and casing having coregistering apertures, one of which is elongated, and circuit wires extending from said reproducer head through said apertures into the casing, and a plug socket in said casing to which said wires are coupled. 15. A reproducer device of the class described comprising a casing, a pivot shaft mounted in the casing and extending through the upper end thereof, a reproducer arm rotatably mounted on the protruding end of said shaft and including a sleeve portion extending into said casing, a cam on said sleeve portion within the casing, two curved control arms pivoted in the casing and normally held in engagement with said cam, a finger projecting radially from said shaft within the casing and in connection with which the free end of said curved control arms operate to control rotary movement imparted to said shaft, said reproducer arm carrying at its free end a reproducer head rotatably mounted in the free end of said arm, and means coupled with said pivot shaft for placing said head in operative engagement therewith to impart rotary movement to the head in the rotation of said pivot shaft, said 30 curved control arms including anti-friction rollers engaging said cam and said finger, means for pivotally and adjustably mounting said casing in connection with a support, adjacent surfaces of said reproducer arm and casing having coregistering apertures, one of which is elongated, and circuit wires extending from said reproducer head through said apertures into the casing, and a plug socket in said casing to which said wires are coupled. 16. A reproducer device of the class described comprising a casing, a pivot shaft mounted in the casing and extending through the upper end thereof, a reproducer arm rotatably mounted on the protruding end of said shaft and including a sleeve portion extending into said casing, a cam on said sleeve portion within the casing, two curved control arms pivoted in the casing and normally held in engagement with said cam, a finger projecting radially from said shaft within the casing and in connection with which the free end of said curved control arms operate to control rotary movement imparted to said shaft, said reproducer arm carrying at its free end a reproducer head rotatably mounted in the free end of said arm, and means coupled with said pivot shaft for placing said head in operative engagement therewith to impart rotary movement to the head in the rotation of said pivot shaft, said 35 curved control arms including anti-friction rollers engaging said cam and said finger, means for pivotally and adjustably mounting said casing in connection with a support, adjacent surfaces of said reproducer arm and casing having coregistering apertures, one of which is elongated, and circuit wires extending from said reproducer head through said apertures into the casing, and a plug socket in said casing to which said wires are coupled.
